Primary Examiner — T. Chase Nelson*Assistant Examiner* — Mark Cavana(74) *Attorney, Agent, or Firm* — IP & T Group LLP(57) **CLAIM**

We claim the ornamental design for an educational robot, as shown and described.

DESCRIPTION

FIG. 1 is a top front perspective view of an educational robot showing the new design; and

FIG. 2 is a front elevational view of the educational robot; FIG. 3 is a back elevational view of the educational robot; FIG. 4 is a right side elevational view of the educational robot; FIG. 5 is a left side elevational view of the educational robot; FIG. 6 is a top plan view of the educational robot; and, FIG. 7 is a bottom plan view of the educational robot.

The broken lines are included for the purpose of illustrating portions of the educational robot that form no part of the claimed design.
